UNITED STATES PATENT OFFICE.

WILLIAM B. H. DOWSE, OF NEWTON, MASSACHUSETTS.

DESIGN FOR A BUTTON-SETTING TOOL.

SPECIFICATION forming part of Design No. 26,767, dated March 16, 1897.

Application filed August 20, 1896. Serial No. 603,418. Term of patent 14 years.

To all whom it may concern:

Be it known that I, WILLIAM B. H. DOWSE, a citizen of the United States, residing at Newton, in the county of Middlesex and Commonwealth of Massachusetts, have invented a new and original Design for Hand Button-Setting Tools, of which the following is a specification, reference being had to the accompanying drawing, showing in perspective a tool embodying my design.

The design is for a button-setting tool comprising two members, which are represented on the drawing and marked A and B, respectively. The part A is a flat plate or base C of oval form, with a bulge c on one of the longest sides. A right-angled rim or flange extends around the circumference of the part or base C. Projecting upwardly from the base and toward each end thereof and at some distance from each other are two short round columns or cylinders D E, and cen-

trally arranged on the tops of said cylinders are short cylinders of considerable less diameter than the cylinders D E. The part B comprises two vertical cylinders E' F, having dome-shaped tops e' f. These cylinders are arranged at some distance apart and are connected by a curved web G, the bottom part of which is concaved, as shown in the drawing. An arm H of substantially pear shape, or with an enlarged end, projects at right angles from the web G and cylinders E' F, and is arranged centrally between them.

I claim—

The design for a tool herein shown and described.

In witness whereof I have hereunto set my hand.

WM. B. H. DOWSE.
